UNITED STATES PATENT OFFICE.

WILLIAM A. COCKRELL, OF CLEVELAND, OHIO.

GRAIN-SCOURER.

SPECIFICATION forming part of Letters Patent No. 319,788, dated June 9, 1885.

Application filed February 13, 1885. (No model.)

To all whom it may concern:

Be it known that I, WILLIAM A. COCKRELL, of Cleveland, in the county of Cuyahoga and State of Ohio, have invented certain new and useful Improvements in Grain-Scourers; and I do hereby declare that the following is a full, clear, and exact description thereof, reference being had to the accompanying drawings, making part of this application.

My invention relates to certain new and useful improvements in that kind of grain cleaning or scouring machines in which there is used a cylindrical case, within which revolve a series of either brush-like devices or mere beaters, or both, rotating in proximity to the inner surface of said cylindrical case, and a suitable fan-like contrivance to create a suction-blast, to ventilate the grain and carry off the dust and other impurities resulting from the cleaning or scouring of the kernels. Previous to my invention machines of this type have been more or less defective and unsatisfactory in their operations and results from various causes, which I propose to wholly or partially remove, thus providing a machine capable of producing much better results than those heretofore employed.

To this main end and object my invention may be said to consist in the several novel features of construction, which will be found hereinafter more fully explained, and which will be specifically pointed out in the claims of this specification.

To enable those skilled in the art to which my invention relates to make and use machines containing either wholly or partially the several features of my improvement, I will now proceed to more fully describe the same, referring by letters of reference to the accompanying drawings, which form part of this specification, and in which I have shown each of the features of my invention carried out in that form in which I have so far successfully practiced it.

In the drawings, Figure 1 is a vertical sectional view of a machine embodying my invention. Fig. 2 is a top or plan view of the same. Fig. 3 is a horizontal section taken at the line $x-x$ of Fig. 1. Fig. 4 is a face view, on an enlarged scale, of portion of the screen or case. Fig. 5 is a cross-section taken at the line $y-y$ of what is shown at Fig. 4. Fig. 6 is

a partial sectional elevation, on an enlarged scale, of one of the brushes employed; and Figs. 7 and 8 are respectively a side and an edge view (same scale) of the wire bristles used in the brush partially shown at Fig. 6.

In the several views the same part will be found designated by the same letter of reference.

A is a vertical shaft arranged centrally of the case A' of the machine, and so as to turn freely in suitable bearings. At the lower end, preferably, of said shaft is secured a pulley, A', through the medium of which motive power is applied to the working parts of the machine.

Surrounding the main shaft A is a sleeve or hollow shaft, B, which is provided at its upper end with a perforated flange or collar, b. The upper end of the shaft A is screw-threaded, and over this portion a threaded hub or nut, c, works, which is provided with a collar, b', similar to that on the end of the sleeve B. Bolts b' b' connect the collars b and b', and thus the shafts A and B are made to turn together. The nut c is provided with a hand-wheel, c', by which it may be turned when it and its connections are to be raised or lowered, for a purpose which will be hereinafter explained. Above the nut c is arranged a jam-nut, e, that is also provided with a hand-wheel, e', for convenience of manipulation.

From the shaft B, at each end, project radially a series of lugs or ear-pieces, d d, to which are pivoted one set of ends of a series of rods or arms, C, the other ends of which are jointed in a similar manner to a series of lugs, d', that project inwardly from the backs D of the scouring-brushes, (or combined beaters and brushes,) as shown.

Instead of using the combined beaters and brushes, such as shown, and in which the side strips or vertical pieces s, (see Fig. 3,) which are secured to the edges of the wooden brush-backs, and the edges of which extend out into close proximity to the internal surface of the scouring-cylinder, act as beaters, beaters of any of the usual forms and used without the presence of any brushes may be employed. Whether brushes or beaters, or both combined, be used, (according to the kind of work for which the machine may be designed,) all the advantages derivable from the use of the

peculiarly constructed scouring-surface will be obtained. By this mode of hanging the brushes E to the hollow shaft B said brushes, which are confined endwise only between the 5 upper and lower heads, f and f', of the cylinder, are rendered capable of adjustment radially by raising or lowering said hollow shaft. Each of the brushes E is composed (see Figs. 6, 7, 8) of a strip of card-clothing formed with 10 staple-shaped straight wire teeth arranged close together in parallel lines, and secured at their roots in a leather holder-strip, e², that in turn is securely cemented or otherwise fastened to the wooden backing D. A brush thus 15 made I have found to work best in my improved machine, because, while presenting a comparatively stiff working-face, no grain can enter between the parallel wire bristles arranged close together, and the working-face 20 acts just right on the kernels of the grain.

F is the metallic cylinder or case of the machine, which, as shown, is composed of a wire woven fabric of the peculiar structure illustrated, (see Figs. 4 and 5,) and is fastened at 25 its upper and lower portions to the wooden case or frame A⁴.

Immediately over the main shaft A is arranged, axially in line with it, a secondary shaft, a⁵, the lower end of which is stepped at 30 h in the top of shaft A, and which is provided at its upper end with a drive-pulley, B².

At one side of the frame or box of the machine is located and arranged to turn in suitable bearing-boxes a vertical shaft, a⁶, which 35 is provided near its lower and upper ends, respectively, with fast pulleys A² and B³, so that by an endless band or belt passing around pulleys A² and A³ the power and motion of shaft A will be imparted to shaft a⁶, and also 40 so that by means of another belt passing around pulleys B² and B³ the rotary motion of shaft a⁵ will be imparted to the secondary shaft a⁵. As the drivers A² and B³ are each of greater diameter than the pulleys A³ and 45 B², that are respectively driven by them, it follows that this system of pulleys operates to "speed up" and cause the secondary shaft a⁵ to run considerably faster than the main shaft A. The object of thus speeding up is 50 to drive the fan H, mounted on shaft a⁵, with sufficient velocity.

In the general operation of the machine the grain to be cleaned falls from a supply-hopper, thence through a spout, e², then falls into 55 the interior of the scouring-cylinder F and in between the combined beaters and brushes, by which the grain is thrown outwardly by centrifugal force toward and against the internal surface of the said cylinder F, between which 60 and the rapidly-revolving brushes E the grain is scoured during its descent to the bottom of the cylinder, where it escapes from the machine through the exit-spout or discharge-conduit m, the grain passing thence downward, 65 while the dust is drawn upward through p, its heavier parts or the chaff being dropped at q.

By reason of the use of a cylinder, F, com-

posed of a woven wire fabric having its superficial projections flattened, as shown and described, the maximum number of small perforations to effect a perfect ventilation is obtained, while at the same time no deep or large cavities occur in the working-surface of the cylinder to permit any lodgment of the kernels of grain, and the best possible character of scouring edges and surfaces is obtained under the most desirable conditions. 70

As shown at Figs. 4 and 5, (where I have illustrated the character of the wire cylinder fabric by showing a piece drawn on an exaggerated scale,) the fabric of cylinder F is a woven wire fabric composed of one set of warp and one set of weft strands, each set of strands being arranged about equidistant, so as to form rectangular meshes of such size as 75 to preclude the entrance or lodgment therein of any kernel of the grain, and at the same time afford opportunity for the passage of the maximum quantity of air or air-blast through the fabric. On the working side or surface of 80 this cylinder all the projecting bends of all the strands are flattened, so as to form a series of facets, as it were, as seen at 1 2 3, &c., which operate to render the face of the fabric flatter, while at the same time reducing 85 the depths of the interstices between the crossing strands, and also forming a series of both vertical and horizontal edges and ledges, the former of which act as cleaners or scrapers, and the latter to retard the descent of the 90 grain being operated upon; but if only the bends of those strands which run lengthwise of the cylindrical case be flattened the main advantages of the kind of scouring-surface will be attained. Therefore I wish it to be 95 understood that in carrying out my invention the facets formed by flattening the bends of those wires running circumferentially of the case may be omitted, though I prefer the form of flattened wire fabric shown. 100

The straight wire brushes, such as shown, acting in conjunction with a cylinder, such as I have shown and described, I have found to be stiff enough to act efficiently in removing all adhering impurities from the entire surface of the grain, while at the same time they will not scratch or abrade the bran, and I therefore deem it desirable in carrying out my invention to use this kind of brushes. 110

By means of the combination of devices 120 shown and described for adjusting the hollow shaft B vertically, and thus moving the brushes and beaters radially, I am enabled to quickly, easily, and perfectly adjust the brushes relatively to the scouring-cylinder F, to compensate for wear in the working-surfaces. Of course the exact degree of fineness to which the wire fabric of cylinder F should be woven, and the degree of flattening of the working-surface of the fabric, whether both or only one 125 set of strands be flattened, may be varied more or less, in the judgment of the maker of the machine, according to the nature or character of the grain to be operated upon 130

by the machine, and many variations in the details of construction of the machine may be made without departing from the gist of my invention. For instance, for the purposes, 5 merely, of a smut-machine, the flattened woven wire fabric may be used for the cylindrical case in a machine having no brushes at all, and provided only with beaters operating to throw the descending grain constantly against 10 the working (internal) surface of said case.

Of course my invention may be applied to machines in which the cylindrical case may occupy an oblique and nearly horizontal position, instead of a vertical one, as shown herein. 15 Having now so fully explained the several features of my improved machine that those skilled in the art can practice my invention, either as to one or more of said features, what I claim as new, and desire to secure by Letters Patent, is—

1. In a machine for cleaning grain, the combination of a scouring-cylinder composed of

a woven wire fabric having one or both of its sets of strands flattened, suitable interiorly-arranged cleaning devices, and means for causing the passage of air-currents through the scouring-cylinder and the material being operated upon, substantially as and for the purposes set forth. 25

2. In combination with a scouring-cylinder, 30 F, composed of a woven wire fabric having the bends of its working-surfaces flattened, as specified, a series of revolving brushes composed of wire, the strands of which are arranged about parallel, and which are backed, 35 as shown and described, to render them comparatively stiff, all as set forth.

In witness whereof I have hereunto set my hand this 5th day of February, 1885.

WILLIAM A. COCKRELL.

In presence of—

A. D. DANA,
T. S. MILLER.
